SAFETY CASH CABINET

Hubert H. Culler and George B. Patterson,
High Point, N. C.

Application June 1, 1933, Serial No. 673,914

3 Claims. (Cl. 109—1)

The invention aims to provide a rather simple and inexpensive, yet a reliable and safe cash cabinet for banks, filling stations, theatres, stores, etc., constructed in a novel manner so that the cash container or drawer may be rendered inaccessible at a moment's notice to frustrate hold-ups.

With the foregoing in view, the invention resides in the novel subject matter hereinafter described and claimed, description being accomplished by reference to the accompanying drawings.

Fig. 1 is a perspective view showing the invention as a distinct unit, although it could well form a part of a desk, table, counter, or the like.

Fig. 2 is a central vertical longitudinal sectional view.

Fig. 3 is a vertical transverse sectional view on line 3—3 of Fig. 2.

Fig. 4 is a view similar to Fig. 3 but showing the relation of parts after the cash drawer has been moved to its inaccessible position.

Fig. 5 is a detail sectional view showing a curtain door which may be used in place of the slide 30.

The specific form of construction herein disclosed, will be definitely described, with the understanding however, that numerous variations may be made within the scope of the invention as claimed, not only with regard to details and proportions, but materials as well, metal construction however being preferable.

The numeral 5 on the drawings denotes a rectangular cabinet which, in the form of construction disclosed, is provided with supporting legs 6, said cabinet having a large opening 7 in its top and an opening 8 in one side, the latter opening serving to permit forward projection of the cash drawer 9. This drawer is provided with a removable till 10 which is removed to gain access to parts within the cabinet, when setting the contrivance after it has been tripped.

The cash drawer 9 is slidably carried by a rectangular supporting frame 11 which is mounted for vertical sliding in the cabinet 5, opposite sides of said supporting frame being provided with vertically elongated guide shoes 12 in the present disclosure, contacting slidably with opposite sides of the cabinet. The frame 11 is provided with a removable cover 13 held against accidental dislocation by dowel pins or the like 14, and when said frame is in its normal raised position as seen in Figs. 2 and 3, said cover 13 is flush with the marginal portion 15 of the cabinet top.

Two U-shaped bails 16 are pivoted at 17 to opposite sides of the cabinet 5 and are adapted to be swung upwardly to the horizontal position shown in Figs. 2 and 3, to support the frame 11 in its normal raised position. To hold these bails in operative position, a prop 18 is hinged at 19 to the cabinet bottom, said prop normally occupying the vertical position shown in Figs. 2 and 3, in which position it directly supports the bails 16.

Pivotedly supported under the cabinet bottom is a shelf 20 held normally in horizontal position by a latch 21, any desired means being provided for releasing said latch when required. In the present showing, a small electric motor 22 is secured to the cabinet bottom and is provided on one end of its shaft with a disk 23. An off-center part of this disk is connected by a pivoted link 24 with the latch 21, so that whenever the motor is energized by closing of a suitably positioned switch, the latch 21 will be released, allowing the shelf 20 to drop, as seen in Fig. 4.

A weight 25 which constitutes the actuator for effecting movement of parts to secure safety of the cash drawer contents, is normally supported by the shelf 20, as seen in Figs. 2 and 3. This weight is operatively connected by one cable 26 with the prop 18 for the purpose of downwardly swinging the latter when the weight is allowed to drop. Weight 25 is also connected by a second cable 27 with a part 28 of the cash drawer 9, which part normally supports the till 10. Cable 27 passes through an appropriate guide 29 at the rear end of the frame 11 and when said cable is pulled by dropping of the weight, 25 it retracts the cash drawer 9 into the cabinet 5. By this time, cable 26 has released arm 18, allowing the bails 16 to swing downwardly as seen in Fig. 4. As soon as these bails are released, the entire money container (11, 13, 9, 10) is free to descend and it is hastened in its descent by the downward pull of the weight 25 and the cable 27.

When the parts reach the lower position shown in Fig. 4, a slide 30 which normally projects laterally from the cabinet 5 as seen in Figs. 1 and 2, is projected inwardly across said cabinet over the cover 13, as seen in Fig. 4. A self-applying lock 31 is provided for locking this slide in its inward position, and said lock may be either of key-released or combination type, so that the slide cannot be released and access gained to the cash drawer, by unauthorized persons.

A cable 32 and weight 33 are provided to project the slide 30 across the cabinet 5, the inner end of said slide however, normally abutting the frame 11 as seen in Fig. 2, and being thereby held.

in laterally projecting position, in which it forms a convenient leaf or extension for the cabinet.

One or more of the cabinets may be used in any kind of a business establishment and whenever advisable, the latch 21 may be released either on one cabinet only or all of them, as circumstances may dictate. Release of this latch allows dropping of the weight 25, causing it to pull upon the cables 26 and 27, moving the cash drawer 9 into the cabinet, releasing the supporting means of the frame 11, and allowing descent of the entire cash container into the cabinet. As soon as the cover 13 clears the inner end of the slide 30, said slide is free to move under the influence of the weight 33, with the result that it is projected across the cabinet above the cash, and securely locked, rendering the cabinet contents inaccessible until the lock 31 is released by an authorized person.

20 To reset parts, lock 31 is released and slide 30 is withdrawn, said slide being preferably held temporarily in withdrawn position by insertion of a pencil or the like between the inner end of the slide and the outer side of the cabinet 5.

25 The cover 13 is then removed, allowing access to the till 10, so that this till can also be taken out. The weight 25 is now supported upon the shelf 20, the latter being held by re-engagement of the latch 21 therewith. Frame 11 is now re-

30 stored to its raised position, the bails 16 are swung inwardly to support said frame, and the prop 18 is swung upwardly to support said bails. The till 10 and cover 13 are then restored to their proper positions and the cabinet is in readiness 35 for further operation, care being exercised however, to remove the pencil or the like which has been temporarily holding the slide 30 in retracted position.

Instead of using the slide 30, a suitably guided 40 curtain door 30' may be used, as seen in Fig. 5, a cable 32' and weight 33' being provided for closing said curtain door in the same manner that the cable 32 and weight 33, close the aforesaid slide 30.

45 We claim:—

1. A device of the class described comprising a

cabinet, a cash drawer carrying frame mounted for vertical movement in said cabinet, releasable supporting means for normally supporting said frame in a raised position, a cash drawer slidably carried by said frame and projectable from the cabinet when the frame is in its raised position, an actuator, releasable means for normally holding said actuator against operation, a cable operatively connecting said actuator with said releasable frame supporting means for releasing the latter when said actuator operates, and a second cable operatively connecting said actuator with said cash drawer for retracting the latter into the cabinet when said actuator operates.

80

2. A device of the class described comprising a cabinet, a cash drawer carrying frame mounted for vertical movement in said cabinet, releasable supporting means for normally supporting said frame in a raised position, a cash drawer slidably carried by said frame and projectable from the cabinet when the frame is in its raised position, a weight and releasable means for normally supporting it against descent, a cable operatively connecting said weight with said releasable frame supporting means for releasing the latter when said weight is allowed to descend, and a second cable operatively connecting said weight with said cash drawer for retracting the latter into the cabinet when said weight descends.

85

3. A device of the class described comprising a cabinet, a money container mounted for vertical movement in said cabinet, two U-shaped bails pivoted in said cabinet and adapted to be swung inwardly under said money container to support the latter in a normally raised position, a prop pivoted in said cabinet and normally occupying a vertical position in which it directly supports said bails against downward swinging, and means for swinging said prop downwardly, allowing downward swinging of said bails and descent of said money container.
